Plas. 458

To all to whom these presents shall come,

Be it known that we Nicholas S

Vedder and William L. Sanderson of the City of Troy County of Rensselaer and State of New York, have invented or produced a new and original design of four boiler hole elevated oven cook Stove which we call the "Mohawk Valley air Sight" and we do hereby declare that the following is a full and exact description of the same reference being had to the annexed isometrical perspective drawing of the stove making a part of this specification.

The ornamental design of our stove consists of arabesque figures (a a) the ornaments (b b) and rosettes (c c) disposed on the panels of the sides, doors and other parts of the stove as represented and in the combination of the mouldings forming the frames of the door, top, hearth etc

What we claim as new and desire to secure by Letters Patent is the ornamental design and configuration of each stove the same as herein described and represented in the annexed drawing.
